UNITED STATES PATENT OFFICE

168,782

CHAIR-DESK

Laurence W. Brulin, New York, N. Y., and Laird F. Covey, Darien, Conn., assignors to American Seating Company, Grand Rapids, Mich., a corporation of New Jersey

Application August 13, 1952, Serial No. 21,033

Term of patent 14 years

(Cl. D33—11)

To all whom it may concern:

Be it known that we, Laurence W. Brulin and Laird F. Covey, citizens of the United States and residents, respectively of New York, in the county of New York and State of New York, and Darien, in the county of Fairfield and State of Connecticut, have invented a new, original, and ornamental Design for a Chair-Desk, of which the following is a specification, reference being had to the accompanying drawing, forming a part thereof.

We claim:

The ornamental design for a chair-desk, substantially as shown.

LAURENCE W. BRULIN.
LAIRD F. COVEY.
